UNITED STATES PATENT OFFICE.

MARCEL PAUL DARCISAC, OF PARIS, FRANCE.

ARTICULATOR.

Application filed February 25, 1924, Serial No. 695,026, and in France February 27, 1923.

My invention relates to apparatus ensuring the correct disposition of the masticating surfaces of complete or partial sets of teeth, bridges, or straightening pieces.

5 To this effect, the physiological movement of the teeth is first recorded in a plastic substance placed in a special apparatus which comprises upper and lower plates disposed in pairs, one plate containing the plastic substance and the other the projections 10 penetrating into the same. The apparatus is placed in the mouth of the patient, and the said plates are held in the proper position. The patient places his jaws in contact with 15 the said apparatus and performs the usual grinding or biting movements whether horizontal or vertical. Due to the said projections, which are thus caused to enter the plastic substance, the movements will be 20 recorded in the latter, and the record will be permanent when the substance becomes hardened.

The plates thus serving for the record are removed from the said apparatus and are 25 mounted upon a special apparatus termed "articulator", containing the moulded models of the upper and lower jaws; when the said models are manipulated by hand in order to imitate the movements of the jaws, the movements made by the patient will be reproduced with great accuracy, due to the presence of the record plates. In this manner 30 the movements will be again recorded in the articulator, which comprises for this purpose a plate provided on both sides with 35 projections for recording the movements in a plastic substance contained in flat vessels or trays disposed above and below the said plate.

40 From this manner, one obtains a recording articulator for the exact transposition of the individual physiological movement of the teeth, after making the direct record upon the person.

45 The appended drawings which are given by way of example show one embodiment of the invention.

Fig. 1 is a perspective view of the upper part of the articulator connected with the 50 moulded plaster model.

Fig. 2 is a like view of the lower part, and Fig. 3 shows a partial elevation.

55 Fig. 4 is a perspective view of the complete articulator, the tray containing the plastic substance being somewhat moved

aside in order to show the arrangement of the recording device.

Fig. 5 is a perspective view of the articulator ready for operation.

Fig. 6 is a sectional view of the recording 60 device of the articulator.

This device comprises two parts, an upper part to which the top moulded portion is secured, and a lower part holding the bottom portion. 65

The upper part, Fig. 1, comprises two rectangular frames 1, 2, which are hinged together at the rear edge at 3; in the said frames are disposed two small metallic trays 4 which are filled with the softened paste 70 at the time of transcription of the physiological movement, and which are held in the said frames by a cover 5 hinged at 6 and fastened by a bolt 7. Between the frames is a space 8 in which is placed a rectangular plate 9 provided on each side with conical projections 10 having at the apex a small mounded point, the said plate is secured to the lower part of the articulator, and it can be given a sufficient play in all directions, 80 between the said frames while the operation is being performed. When the transcription has been effected and the plastic substance has become hardened, the same will move according to the recesses formed by the 85 said projections in the paste, Fig. 6, and this will enable the exact reproduction of the movements of the jaws. At the front part of the upper frame is provided the anchoring piece 11 which is imbedded in the plaster 90 model and serves to attach the device thereto. 95

Upon the rear end of each frame and on either side of the hinge, is disposed a guide 12 co-operating with a bolt 13 provided with a button 14; when the said bolt is at the top, it will lock the hinge, and when at the bottom the hinge is released.

The lower portion, Figs. 2 and 3, comprises two vertical plates 15 forming parallel sides and connected by the top plate 9; the latter is provided on both faces with conical projections 10, six or eight in number. The said top plate or recording plate is disposed, as above stated, between the two frames of the upper part. Between the inner faces of 100 the side plates 15 and the outer edge of the lower frame 2 of the upper part is allowed a space of a few millimeters which provides for the lateral play of the lower part. The side plates 15 are secured at the lower part 105 110

of their front edge to the anchoring member 16 imbedded in the lower model; at the rear end of said plates are disposed the closed guides 17, 17, which in the position of contact of the teeth, coincide with the guides 12 of the upper part of the apparatus. When the said locking bolt is at the top, it locks the hinge of the two frames and at the same time releases the lower part of the 10 apparatus; when the bolt is at the bottom, Fig. 4, it releases the hinge of the two frames, thus permitting the removal of the model attached to the upper frame from the opposite model, but it secures the lower part 15 of the upper portion of the apparatus to the lower frame; a screw 18 upon the rear face of each lower guide serves to complete the fastening. In this latter case, the apparatus operates as an occlusion device of the single 20 type. The device for anchoring in the plaster models may comprise a metal strip 19 which is movably secured to the apparatus by a dovetailed guide 20.

The operation is as follows:

25 The two plaster models are adapted to the articulator which is employed as an occlusion device, and the locking bolts are now in the bottom position; then after attaching—by adhesive wax—the base plates upon 30 which the six front teeth have been mounted, as well as the recording plates which were used to register the physiological movement, and after taking care to give a good coating of vaseline to both sides of the recording 35 plate of the lower portion of the articulator, I proceed as follows:

The bolts 13 are placed in the top position, so as to fasten the two frames of the upper portion (Fig. 5) and the upper tray is released by opening the cover (Fig. 4), then after filling it with plastic substance (Crown extra-hard), it is put in place and the cover is closed. The models are then held one in each hand and they are made to slide upon 40 one another (Fig. 5); reproducing the movements of grinding the teeth which have been recorded in the mouth; this is carried out until the plastic substance in the tray has become completely hardened. The same operation is performed with the lower tray. When the transcription is completed (Fig. 45) the bases of the models can be removed; these latter will maintain the given relation of the physiological movement. I then proceed with the mounting of the pieces of dental work, whose masticating surfaces can be correctly formed. A strong elastic handle or strap, not shown, may be used with the apparatus, so that the lower part of the articulator can be brought automatically to the rear and to the top in the position of occlusion; one or two springs secured to the lower frame of the apparatus will produce the same result. During the preparation of the 55 small models, the rear locking bolts will be

lowered when it is desired to separate the two principal models, and the bolts will be again raised to the top when it becomes necessary to regulate the triturating surfaces.

70

By reason of the removable disposition of the models and of the transcribing trays, the said apparatus can be utilized for a number of sets of dental work at the same time, and should it be considered necessary, the models can be preserved together with the record of their physiological movement, due to the use of additional trays.

75

On the other hand, since the spacing between the upper edge of the side plates and the lower edge of the upper frame during the movement of the propulsion of the teeth (Fig. 5) will show the inclination of the condylian plane, I am enabled to make the proper choice of the teeth for each particular case; a ruler or a graduated pointer can be provided in order to enable the choice of a type of teeth whose friction faces correspond in the individual condylian plane, and which can be chosen out of three or four shapes.

80

Having thus described my apparatus, what I claim as new therein, and my own invention, is:

1. An articulator for the exact mounting of artificial teeth, comprising two elements adapted to receive the molded plaster models of the two jaws, two trays secured to one of the said elements and adapted to contain a plastic substance, said trays being superposed with their operative faces towards each other, a plate secured to the other portion and disposed between the two trays, said plate having various projections upon both faces which may be pressed into the plastic substance contained in the said trays, and pivoting means serving to connect together the two hinged portions.

85

2. An articulator comprising two elements adapted to receive and to rigidly maintain the molded plaster models of the two jaws, respectively, a frame adjustably mounted upon one of the said elements, a second frame hinged to the first-mentioned frame, two trays fitted respectively into the said frames, the concave sides of the said trays being inwardly disposed and thus facing each other, a support comprising two uprights and two cross-pieces, one of the said cross-pieces being adjustably secured to the second element supporting the plaster model, while the other cross-piece is provided with conical projections upon both faces and is adapted for insertion between the two trays above mentioned, and means rigidly connecting one of the said frames with the said support.

100

In testimony that I claim the foregoing as my invention, I have signed my name.
